FIG. 4

FIG. 3

FIG. 1

FIG. 2

FIG. 1 is a front perspective of an agricultural implement for spreading or sowing granular and powdered materials showing my new design;

FIG. 2 is a rear perspective thereof;

FIG. 3 is a perspective view of the storage hopper with portions of the implement structure omitted for convenience of illustration;

FIG. 4 is a perspective as seen from the rear of FIG. 3;

FIG. 5 is a top plan view of the storage hopper;

FIG. 6 is a rear elevation of the hopper and frame structure; and

FIG. 7 is a side elevation thereof.

The dominant features of my design reside in the portions shown in full lines.

This is a continuation-in-part of design application Serial No. 85,276, filed May 14, 1965 and now abandoned. I claim:

The ornamental design for an agricultural implement for spreading or sowing granular or powdered materials, as shown and described.
